GARMENT SAFETY PIN FASTENER

Filed Nov. 2, 1950

INVENTOR
Thomas Yanagihara,

BY Gustave Miller
ATTORNEY

urge the hook points 14 into the housing 11 to the position beneath the bar portion 24 as shown in Fig. 10, in the cloth or fabric penetrating and holding position there shown. The stop pins 25 act as guides for the hook legs 16 and hold such legs 16 in sliding engagement with the inner surface of the back plate portion 17. In addition, the stop pins 25 located beneath the bar portion 23 serve to limit or stop the movement of the hook 12 through the housing in the direction urged by the springs 27, the point legs being of such length that the points 14 are held beneath the bar portion 24 when in closed position, while the stop bridge 26 and the springs 27 under compression absolutely prevent the removal of the hook in the opposite direction and prevent the point 14 from being moved to a position beyond the end of the bar plate portion 23, thus keeping the points 14 in a safe position at either end of their movement.

In operation, the housing 11 and the hook 12 may be moved relative to each other to move the fabric penetrating points 14 between the two positions shown in Figs. 3 and 10 from beneath one of the front bar portions 24 to beneath the other of the front bar portion 23, the springs 27 normally urging it to the position beneath the bar portion 24.

To use the garment safety clip 10 of this invention as a diaper holder, for instance, the housing 11 may be grasped by its sides and then the hook 12 moved to the open position by pushing the bight 15 of hook 12 toward the housing, compressing the spring 27, and then grasping the bight 15 in the fingers of the same hand holding the housing 11, then, with the other hand, the portions of the diaper to be engaged and held are placed in the space in the housing between the edges of front bar portions 23 and 24 and the bight 15 is then released, causing the point 14 to penetrate through the fabric 32 of the diaper to the position beneath the front bar plate 24, as shown in Fig. 10, the penetrating movement being assisted, if necessary, by grasping the bight 15 as a handle and pulling it through. Once in engaged position, the spring 27 will be of sufficient strength to normally prevent accidental removal of the point 14 from the garment or diaper 32, particularly by the fingers of a child or baby on whom the diaper is placed.

When used as a suspender hook, the suspender strap 33 may be sewed as at 34 about the bight 15 and the fabric to be supported is then placed in the space between the front bars 23 and 24 for engagement in a similar manner.

Instead of sewing the suspender strap 33 to the bight 15, a cross bar 35 may be provided about the legs 16 adjacent the bight 15', and the bight 15' is provided with a pair of fabric engaging teeth 36, so that a suspender strap 37 may be folded about the cross bar 35 and then brought under the bight 15' against the teeth 36 and be held thereby, as shown in Figs. 8 and 9. Otherwise, the construction of this modification may be identical with the first form already disclosed.

As an additional modification, the spring 27 and its washers could be omitted with the omission of its function, of normally urging the hook to the closed position.

However, with the springs present is preferable, not only when intended for use as a diaper clip, but also in other uses. As in suspenders, for instance, the presence of the spring 27 will

be sufficient to prevent the housing 17 from riding up and forcibly disengaging the garment secured by the hooks 12.

While the device has been shown and the structure described in detail, it is obvious that this invention is not to be considered as being limited to the exact form disclosed, and that changes in detail and construction may be made therein within the scope of what is claimed, 10 without departing from the spirit of this invention.

Having thus set forth and disclosed the nature of this invention, what is claimed is:

1. A garment safety clip comprising a housing member and a hook member moveable within said housing within limits, said hook member comprising a wire rod folded into a U, parts of the legs of the U being folded back parallel to the plane of the U in a plane with an intermediate part of each leg at right angles thereto, the legs terminating in points, said housing comprising a back plate portion, sides on said back plate portion folded at right angles thereto, and extending a distance substantially equal to the 20 diameter of said wire rod, spaced apart front bar portions having folded side portions integrally extending from the side portions of said back plate portion, hook guide and stop means extending through said side portions a distance into said housing greater than the diameter of said wire rod and spaced from the inner surface of said back plate portion a distance substantially equal to the diameter of said wire rod, and means preventing the movement of the U-bight through 30 said housing.

2. A garment safety clip comprising a housing member and a hook member moveable within said housing within limits, said hook member comprising a wire rod folded into a U, parts of the legs of the U being folded back parallel to the plane of the U in a plane with an intermediate part of each leg at right angles thereto, the legs terminating in points, said housing comprising a back plate portion, sides on said back 40 plate portion folded at right angles thereto, and extending a distance substantially equal to the diameter of said wire rod, spaced apart front bar portions having folded side portions integrally extending from the side portions of said back plate portion, hook guide and stop means extending through said side portions a distance into said housing greater than the diameter of said wire rod and spaced from the inner surface of said back plate portion a distance substantially equal to the diameter of said wire rod, means preventing the movement of the U-bight through 50 said housing, and yieldable means about the legs of said U between the U-bight and the housing normally urging said hook to the closed fabric holding position.

3. A garment safety clip comprising a housing member and a hook member moveable within said housing within limits, said hook member comprising a wire rod folded into a U, the legs of the U being folded back parallel to the plane of the U in planes at right angles thereto and terminating in sharp end points, said housing comprising a back plate portion, sides on said back plate portion folded at right angles thereto, and extending a distance substantially equal to the 60 diameter of said wire rod, spaced apart front bar portions having folded side portions integrally extending from the side portions of said back plate portion, hook guide and stop means extending through said side portions a distance

into said housing greater than the diameter of said wire rod and spaced from the inner surface of said back plate portion a distance substantially equal to the diameter of said wire rod, and means preventing the movement of the U-bight through said housing, and yieldable means about the legs of said U between the U-bight and the housing normally urging said hook to the closed fabric holding position, said yieldable means comprising a coiled compression spring about each leg.

THOMAS YANAGIHARA.
